(57) **CLAIM**

The ornamental design for a front portion of a retaining wall block, as shown and described.

DESCRIPTION

FIG. 1 is a perspective view of a front portion of a retaining wall block according to our new design;

FIG. 2 is a top plan view of the front portion depicted in FIG. 1; a front elevation view of the front portion depicted in FIG. 1;

FIG. 3 is a bottom plan view of the front portion depicted in FIG. 1;

FIG. 4 is a front elevation view of the front portion depicted in FIG. 1;

FIG. 5 is a right side elevation view of the front portion depicted in FIG. 1; and,

FIG. 6 is a left side elevation view of the front portion depicted in FIG. 1.

The broken lines in the drawings illustrate an embodiment of the structural environment of a retaining wall block that include the front portion of the design and is not part of the design sought to be patented.
